COMBINATION TOOTH BRUSH AND CASING

Harold Fredrickson, Minneapolis, Minn., assignor to
Lactona, Inc., Ramsey County, Minn., a corporation of
Minnesota

Application April 19, 1956, Serial No. 41,132

Term of patent 14 years

(Cl. D9—2)

FIG. 1

FIG. 2

FIG. 3

FIG. 6

FIG. 4

FIG. 5

Figure 1 is a perspective view of a combination tooth brush and casing in open position, showing my new design;

Figure 2 is a perspective view of the same in collapsed position;

Figure 3 is a side elevation of the brush end of the same;

Figure 4 is a side elevation view of the handle end of the same;

Figure 5 is a top plan view of the handle end of the same; and

Figure 6 is an end elevation view of the same in collapsed position.

I claim:

The ornamental design for a combination tooth brush and casing, as shown.
